UNITED STATES PATENT OFFICE

2,260,020

KNITTING MACHINE

Isaac H. C. Green, Central Falls, and Eugene St. Pierre, Pawtucket, R. I., assignors to Hemphill Company, Central Falls, R. I., a corporation of Massachusetts

Application March 4, 1940, Serial No. 322,140

7 Claims. (Cl. 66—41)

This case involves an invention in certain mechanism as applied to knitting machines for incorporating elastic yarn and for producing a selvage in which elastic is incorporated along with a non-elastic yarn in a particular manner more or less as disclosed and claimed in co-pending application Serial #295,095, filed September 15, 1939.

In the figures of the drawings:

Fig. 1 is an elevation of part of a knitting machine to which the invention has been applied;

Fig. 2 is an elevation showing a needle cylinder and sinker assembly as well as some of the cams and their control along with selecting means as applied to one form of the invention;

Fig. 3 is a section taken through the needle cylinder and showing in plan view many of the cams functioning upon needle butts;

Fig. 4 is a detail of a knitting cam and part of its controlling means, this knitting cam being used to draw down needles at the elastic yarn feed;

Fig. 5 is a detail showing certain of the connections to the cam shown in Fig. 4 for withdrawing the same;

Fig. 6 is a section taken through a part of the needle cylinder and showing a jack dividing or selecting cam, its support and part of the controlling means therefor;

Fig. 7 is an elevation showing part of the cylinder and the mechanism of Fig. 6 as seen from the front of the machine;

Fig. 8 is a detail view of stopping or limiting means applicable to the cam shown in Figs. 6 and 7;

Fig. 9 is a plan of the sinker cap, parts being cut away so as to show some of the detail of the sinker cams;

Fig. 10 is a section taken through the line 10—10, Fig. 9.

Fig. 11 is a detail of part of the sinker cap assembly adjacent the auxiliary sinker cam at this section 10—10;

Fig. 12 is another detail of the sinker cap showing how the same is cut away adjacent the auxiliary sinker cam;

Fig. 13 is a diagrammatic view showing cams and needle and jack butt paths during knitting in which elastic is being incorporated in a fabric;

Fig. 14 is a similar diagrammatic view, but showing knitting with a non-elastic yarn and ornamentation by needle wrapping;

Fig. 15 is a similar diagrammatic view showing a reverse or clockwise stroke as in the heel or toe of a stocking;

Fig. 16 is a section taken through part of a needle cylinder and showing certain cams which function upon needle butts according to a modified form of the invention;

Fig. 17 is a section taken on the line 17—17, Fig. 16;

Fig. 18 is a detail view showing the elastic yarn knitting cam and part of the control therefor;

Fig. 19 is a section taken on the line 19—19, Fig. 16;

Fig. 20 is a section taken through the needle cylinder and at a level below the needle cam carrying plate and showing selecting means as applicable to jacks, also part of the control therefor;

Fig. 21 is an elevation showing the parts illustrated in Fig. 20 as seen from the front of the machine;

Fig. 22 is a plan of the sinker cam cap showing the general arrangement of sinker cams and control therefor;

Fig. 23 is an elevational view of a fragment 20 of the sinker cam cap assembly adjacent the auxiliary sinker cam; at line 23—23;

Fig. 24 is a section taken on the line 24—24, Fig. 22;

Fig. 25 is a section taken on the line 25—25, Fig. 22;

Fig. 26 is a section taken just in advance of the main yarn feed and showing supporting means and certain cams including both movable and fixed jack selecting and controlling cams;

Fig. 27 is a similar section but taken at a point in advance of the first jack selecting means in a modified form of the invention, and illustrating special control for some of the jack selecting and controlling cams;

Fig. 28 is a detail view of means for controlling plain sole cams;

Fig. 29 is a detail of a movable cam adjacent the main yarn feed, said cam being mounted in a position as illustrated in Fig. 26;

Fig. 30 is a detail of a movable cam adjacent but below the cam illustrated in Fig. 29;

Figs. 31 and 32 are movable cams adapted to function on jack butts in advance of the main feeding station to control knitting or tucking;

Fig. 33 is a detail of a cam similar to that illustrated in Fig. 30, but operative between the first and second selecting means;

Fig. 34 is a detail of a movable cam functioning along with the cam illustrated in Fig. 33, but adapted to raise jacks to a slightly high elevation;

Fig. 35 is a detail of a plain sole cam;

Figs. 36 and 37 are details of a fixed cam for returning jacks to non-selected position after they have been actuated by the first group of 55 selecting means;

Fig. 38 is a diagrammatic view showing cams and the needle and jack butt paths as incorporating elastic according to the modified form of the invention; and

Fig. 39 is a similar diagrammatic view, but

showing knitting during a reverse stroke in the heel or toe.

In the incorporation of elastic yarn according to St. Pierre Patent #2,131,720, the elastic is knitted independently at a separate feeding station and upon spaced needles, preferably every other needle. It is floated behind intervening needles. A non-elastic yarn is fed at the so-called main yarn feeding station and is knitted on all needles at that point. In the construction of the edge of a fabric such as a stocking top, several different types of edge have been made, one so-called "tuck" edge has been found very satisfactory, said edge and general method of producing the same being described and claimed in co-pending application Serial #295,095.

To make this tuck edge along with continuing fabric as in Patent #2,131,720 very specialized mechanism has been developed. In one form of the invention herein illustrated and described by way of example, a Banner 8-step wrap machine has been constructed to knit such an edge, and in a second form herein illustrated as a modification, a so-called 19-step Banner wrap machine is illustrated. It is to be understood that such an edge may be knitted without knitting a wrap pattern either in the edge or the continuing fabric. In such event so much of the mechanism herein illustrated as is necessary to that end may be employed. The particular combination does, however, make use of certain of the wrap controlling devices giving to them the dual function of serving to produce wrap ornamentation, and at appropriate times, to impart the necessary needle control for incorporating the elastic either in the knitted fabric such as illustrated in Patent #2,131,720 or in the edge according to the application Serial #295,095.

Referring to the figures of the drawings, such as Figs. 1, 2 and 3, enough of a typical hosiery machine has been shown to illustrate the important features of the invention. A frame 1 carries a base 2 in which is adapted to rotate a needle cylinder 3. This needle cylinder carries the usual complement of needles, preferably latch needles although other types such as spring beard or sliding latch needles may be employed. Sinkers of conventional type are adapted to be controlled by certain cams in a cam cap 4, said sinkers being slidable in a沉器 head 5. A carrier ring 6 of usual type is extended at one side to mount several yarn feeding levers which are controlled to drop to and be raised from yarn feeding position at a so-called main feeding station or mouthpiece. These yarn levers are controlled as described in United States Patent #933,443. A main cam shaft 7 carries several drums thereon on which are arranged cams for controlling the functions of the machine throughout the cycle of knitting a stocking. Only such cams as are employed in the operation of the mechanism herein described will be mentioned.

A main cam block designated by numeral 8 is mounted on a cam plate 9 supported on a post 10. The main cam block is of the usual construction in that it has a front stitch cam 11, rear stitch cam 12, center guard cam 13 and a center raise cam 14, this center raise cam and the front stitch cam 11 being of rather different construction from that usually employed. These cams, probably best shown in Figs. 14 and 15, are supplemented by a raise cam 15 and a cam 16, the purpose of which will be more fully described in due course. The front stitch cam 11 is movable so that the same may be with-

drawn from engagement with needle butts or may be allowed to engage those butts in which event it will raise butts to a clearing position. The cam 16 has projecting wings 17 and 18 and a V-shaped projection 19 between the two wings. The front stitch cam 11 is much thinner than usual to allow the wing 18 to be positioned in front of center raise cam 14.

The needles, one of which is indicated at 20, Figs. 13 and 14, have jacks 21 beneath them, those jacks having a plurality of selecting butts 22, in this instance eight such selecting butts being available since this is what is termed an 8-step machine. These butts 22 are removable at will as by breaking. The topmost one of these selecting butts is square or rectangular in shape whereas the remainder are of saw-tooth shape. The top butts are of two lengths, short butts 23 alternating with long butts 24. A butt 25 common to all jacks serves to lower them upon engagement with certain cams. Adjacent the upper end of each jack is a master butt 26 which is for the purpose of imparting greater movement to a jack than will be forthcoming from the selective movements imparted through butts 22, 23 or 24. The needles have butts 27, there being a more or less equal division of long and short butt needles for the usual purpose.

A plurality of selecting cams or plungers 28 are slidable to and from engagement with butts 22, 23 or 24, these plungers being slightly inclined and adapted to raise jacks, butts of which have been engaged, to such a position that the master butt 26 will be raised by a cam 29, Fig. 13, the primary purpose of this cam 29 being to elevate selected needles so that they may take a wrap yarn or yarns *w* fed through wrap yarn feeding means generally indicated at 30, Fig. 14. This wrap yarn feeding means 30 is preferably of a type illustrated in United States Patent #1,702,608 but may be of any convenient and effective construction.

A main knitting yarn which is a non-elastic yarn is shown at *y*, Fig. 13, and feeds through one of several yarn feeding guides or levers 31. An elastic yarn feeding finger 32 is adapted to be moved to and from feeding position and feeds the elastic yarn *e*. This finger 32 is fixed at the end of a lever 33 pivoted at 34 and spring pressed into a lower or feeding position, but movable by a contacting lever 35 and other mechanism controllable from certain cam means upon the machine, the remainder of this mechanism not being illustrated since it is shown in co-pending application Serial No. 100,908, filed September 15, 1936.

The selecting cams or plungers 28 are controlled at times by one series of discs having pattern formations thereon and at other times by another such series of discs. The two groups of these discs are indicated at 36 and 37, Fig. 1. They are mounted for rotation upon a drum 38 which is ratcheted by suitable ratcheting means to effect the necessary changes in the placement of the cams 28 to accomplish the knitting of the elastic top, and of the wrap pattern in the leg or other part of a stocking. One group of these cams is employed throughout the knitting of the elastic top and another group in the knitting of the pattern in the leg of the stocking, this all being described and claimed in United States Patent #2,208,698.

The selection of needles at the elastic yarn feeding point is accomplished by one of the plungers 28, preferably the topmost one shown in full lines, Fig. 13. This plunger merely works upon

the butts 24 which are present on jacks beneath every other or alternate needles. Of course, if other than a 1 x 1 division of needles is to be obtained, the arrangement of these butts 24 would be in accordance. When every other jack is raised by the topmost plunger of the group 28, the master butts 26 on those jacks will then be raised just enough so that cam 29 will then raise those jacks to a higher level, one high enough so that the appropriate needles will take the yarn e in their hooks. Those needles raised to a height dictated by cam 29 clear their latches while needles which are not raised by the jack selection neither clear their latches nor do they take the elastic yarn e.

Those needles which do take the elastic yarn are caused to draw it into knitted stitches as their butts are guided down by the auxiliary stitch cam 39, Fig. 13. Naturally all needles are drawn down by this stitch cam 39, but the intermediate needles which were not raised by the jacks are merely drawn down in an idle movement since they did not clear their latches. After the elastic stitches have been drawn needles are raised by the V-shaped projection 19 on the cam 16 and thereafter by the wing 18 which is at a common level with the front edge of cam 14.

Neither of cams 18 nor 14 raises needles high enough for the latches thereof to be cleared. The front stitch cam 11 would perform that function if it were in place, however, in order to knit tuck stitches at the edge of the fabric, or at any other place, that cam must not be in position or all needles would clear and knit. Taking advantage of the long butts 24 on the jacks, a selecting or guiding cam 40, Fig. 13, is movably mounted to be projected in for engagement with said butts on the jacks for raising them and their attendant needles to a latch clearing position, that is, at least as high as they would be raised by the upper point of the front stitch cam 11. That is, according to the arrangement of the long butts 24, any desired needles may be raised for knitting and those not so raised will take yarn, but will not knit. They will tuck the yarn thus taken, the extent of the tucking being dependent upon the time during which cam 11 is withdrawn.

Referring to Figs. 2, 3, 4, 5, 13, 14 and 15, the auxiliary stitch drawing cam 39 is fixed to a carrier 41 which is in turn slideable in the bracket 42. This carrier 41 has one side flattened to align with the inclined edge 43 of the bracket, this serving to maintain the cam at the desired angle. At the outer end of carrier 41 is an angular piece 44 having a projection 45. A spring 46 connects to a projection on the bracket and to another depending extension 47 on the angular piece 44 normally tending to maintain the cam inwardly against the cylinder. A bell crank having arm 48, 49 and 50 pivots at 51' and by means of the depending arm 50 which contacts the projection 45, is effective to withdraw cam 39 when desired. Movement is imparted to the bell crank through a link 51 and connects as leading from that element to cams on the drum which may be any suitable drum on the machine convenient for the purpose.

Referring to Figs. 2, 6, 7 and 8 the cam 40 which is a selecting or dividing cam for clearing needles at the main knitting point when tucking is fixed to the end of a lever 52 pivoted at 53 beneath plate 9. The pivot 53 is threaded into a lug 54 which is a part of, or at least attached to a bracket 55, Figs. 6, 7 and 8. In a depending part of this bracket is threaded a stop screw 56 locked

in position by another screw 57. The outer end 58 of the lever 52 is adapted to contact against this stop screw 56 and thereby limit the inward movement of cam 40 against the cylinder. A link 59 connects to the outer end of lever arm 58 and imparts movement to the lever and thus to the cam 40 for withdrawing the same or allowing it to move in for contacting jack butts, all in accordance with said cams on a cam drum hereinafter to be described.

Now referring to Figs. 1, 2 and 9 through 12, a certain amount of the sinker and sinker cam assembly has been shown mainly for illustrating the control of sinkers at the auxiliary or elastic yarn feeding side of the machine. Sinkers 60 of more or less the usual type are slideable in sinker head 5 and controllable by a plurality of cams in the sinker cam cap generally designated by numeral 4. These cams include side sinker cams 61 and 62 and the center sinker cam 63 functioning at the main feeding station. At the auxiliary feed at which elastic yarn is introduced, there are provided the sinker cams 64 and 65 and a center sinker cam 66. The side cams 64 and 65 are fixed in position, but the sinker cam 66 is movable. This sinker cam 66 is attached at the inner end of a slide 67 adapted to move laterally of the machine and having at its outer end a depending lug 68. The slide 67 is urged laterally inward by a spring 69. Movement is limited by a pin 70 slideable in a slot 71 and limited by a second slot of predetermined length in the adjustable cap 72. The upwardly extending arm 48 of the bell crank previously described with respect to Fig. 4 is bent laterally as at 73, Fig. 2, and engages lug 68 for withdrawing the center sinker cam 66 whenever stitch cam 39 is moved to active position. This assures that a sinker wave occurs concurrently with the needle wave, and vice versa.

Referring to Fig. 1 the control for the stitch cam 39, sinker cam 66 and also for the jack cam 40 have been shown. The link 59 extends downwardly to connect at one end of a lever 74 projected at the upper end of a bracket 75 which is in turn attached to extension 76 from the machine frame. At the other end of lever 74 is pivoted a depending bar 77 engageable with a cam 78 on drum 79. When the end of bar 77 drops from the cam 78, the bell crank having levers 48, 49 and 50 is swung in such a direction that cam 39 is pulled outwardly and sinker cam 66 is allowed to move in so that neither a needle wave nor sinker wave is set up at the auxiliary or elastic yarn knitting point. When the bar moves upwardly on a cam the reverse takes place.

Referring to Figs. 1 and 6, link 59 for controlling cam 40 connects to one arm 80 of a bell crank lever, the other arm 81 of said lever connecting to a depending link or rod 82 which in turn connects at its lower end to a lever 83 engageable with a cam 84 on drum 85. When this cam 84 raises the end of lever 83, cam 40 moves inwardly to engage jack butts. Upon falling from cam 84, the said cam 40 moves outwardly under the influence of a spring (not shown). Of course, at that time, front stitch cam 11 will have been moved into place by mechanism not shown, but controlled from a cam on one of the drums illustrated in Fig. 1.

Operation

Now referring to Figs. 13, 14 and 15 the operation of the machine will be described in three 75 different phases of the knitting. In Fig. 13

needle and jack butt pathways for knitting in an elastic top are shown. The pathway 86 is that of butts 23 and 24 on the jacks 21, those jacks first having been moved upwardly by a cam 87 shown in dotted lines and operable on the master butts 26. By that means all jacks are presented to the plungers 28. The topmost plunger is set to engage long butts 24 and raise them to the elevation 88 which also raises the butts 26 to an elevation 89 thereby permitting cam 29 to raise those jacks to a height sufficient for causing the needles to clear their latches and to take the yarn *e* in their hooks. The needle butts 27 rise in the pathway 86 and are thereafter drawn down by cam 38 to a stitch drawing level. Jacks having butts 23 not affected by the topmost plunger 28 merely pass along in pathway 86 until pushed downwardly along with the long butt jacks in a pathway 91. The butts 26 incidentally move down under cam 16 as shown. The jacks having long butts 24 will next be contacted by the dividing cam 40 and will be raised in a pathway 92. Corresponding needles will rise up in pathway 93 while the remaining needles are raised to a lesser height since their butts merely engage cam 19 and wing cam 18 and along the top of cam 14, needles taking yarn at that height, but not clearing their latches. Needles which did clear their latches are drawn down by cams 13 and 12 and actually knit. The cam 15 merely raises needles to the usual raise cam level. All jacks are pushed down to lowermost position as the needles move under stitch cam 12 and butts 23 and 24 pass along at a level 94 until cam 87 again becomes effective. A cam 95 has been shown in these figures and is employed during needle wrapping as is illustrated in Fig. 14.

In Fig. 14 knitting at the main side only in conjunction with needle wrapping is illustrated. All plungers 28 may be employed at some time in the wrapping and impart eight steps of selection, jacks first being raised by the cam 87 as previously described whereupon plungers 28 effect certain selections and master cam 29 acting upon master butts 26 will raise selected needles in a pathway 86 so that a wrap yarn *w* will be taken in the hooks of appropriate needles. Wing cam 17 pushes jacks downwardly to a lowermost level 97. The butts of selected needles move along at an uppermost level until they reach the depending projection 95 of the cam 95 and are moved downwardly so as to pass beneath center guard cam 13. Incidentally, they are moved low enough so that they are first raised slightly by cam 11 before striking cam 13. The butts of non-selected needles move along at a level 88 until they contact cam 11 whereupon they are raised to clear their latches. They join the upper group at this point and all needles are caused to knit as their butts pass beneath cams 13 and 12. Then needles rise to the ordinary raise cam level as their butts rise up cam 15.

Referring to Fig. 15, needle and jack butt paths are shown in a reverse stroke of knitting as in the heel or toe. For simplicity of illustration short butt pathways only are shown. The jacks do not play an effective part in this knitting and would pass along at a lowermost level except for the influence of the cam 87. That cam does affect the jacks since master butts 26 contact the cam in either direction. In reverse strokes these butts move up the cam 87 and are immediately moved downwardly by a cooperating cam 98. In strokes in the opposite direction they would ride up the cam 87 and would be 75

moved down by the wing cam 17. Neither movement has any effect upon the needles themselves. In clockwise strokes needle butts move along the raise cam 15, pass up cam 12, then beneath cam 13 and down below cam 11 taking yarn and drawing stitches. The V-shaped projection 19 then moves the needles up to a pathway 100 and wing cam 17 gives an additional movement to the ordinary raise cam level. In the opposite direction the butts would merely move along raise cam 15 from the left to the right, beneath cam 15 and over the cam 16 striking cam 11 by means of which latches would be cleared, and thereafter drawing yarn and knitting beneath cams 13 and 12.

Modification

Now referring to Figs. 16-39, a modification has been illustrated, the invention being applied to what is commonly known as a Banner 19-step wrap machine. The general arrangement of parts and principles employed are very similar to those described in connection with the 8-step machine first illustrated, but certain points of difference will be evident from the following disclosure.

In Fig. 16 a cam plate 101 surrounding a needle cylinder 102 carries a cam block 103 having a front stitch cam 104, top center guard cam 105 and a rear stitch cam 106. The center raise cam 107, Fig. 38, is of slightly different construction from that usually employed and has a supplemental cam 108 movably mounted and controlled by suitable mechanism to be moved in and out at desired times. The operation and function of this cam will be more thoroughly described at a later point in the specification.

A bracket 109, Figs. 16, 17 and 18, is mounted on cam plate 101 and carries a slide 110 to the inner end of which is fastened an elastic stitch drawing cam 111. This slide is movable inwardly and outwardly having at its outer end a depending extension 112 being connected by a spring 113 to a fixed part of the bracket 109 so that normally the slide and cam 111 will be moved inwardly against the needle cylinder. A stop screw 114 is adjustable for limiting inward movement. A projection 115 is engaged by a depending arm 116 on a bell crank lever pivoted at 117 on an angular upright 118. This bell crank has a horizontal arm 119 connected to a depending link 120 by means of which the bell crank is moved and the cam withdrawn to an inactive position at predetermined times. A third arm 121 extends upwardly and is employed for the purpose of controlling a sinker cam as will be explained in more detail in due course.

In Figs. 20 and 21 parts for operating upon jacks beneath needles have been illustrated, both the jacks and the jack operating devices being generally located above the circular base of the machine and beneath the cam plate 101. In Fig. 38 a needle 122 has a butt 123. These needles are preferably of the usual latch type and are divided into two groups of long and short butts as is the common practice. Beneath each needle is a jack 124 having a master butt 125 and a plurality of selecting butts 126. The butts 126 are removable at will and may be broken away or otherwise detached in setting up a pattern. Each of the jacks has a square butt above the selective butts, some having short butts 127 and others having long butts 128. If the elastic is to be incorporated according to a 1 x 1 division of needles, alternate needles will have jacks with a long butt 128 while intermediate needles will have the

opposite type of jack, that is, one with a short butt 127.

Since this machine is a 19-step type there will be nineteen of the butts 126. In the selecting of needles as for determining the pattern in the wrap areas, series of selecting plungers 129 and 130 are spaced as shown in Fig. 38. The employment of two sets of these plungers makes possible the knitting of "color side of color" and "color within color" patterns. Briefly, these sets of plungers and associated cams are used for the selecting of needles which are to take elastic yarn at the auxiliary side and to determine the knitting of tuck stitches at the edge of the fabric as at the selvage or adjacent thereto.

First in selecting jacks and thereby needles to take an elastic yarn *e* fed at a so-called auxiliary feeding station, the topmost plunger 129 is used and functions upon the appropriate butt 126 on jacks of needles to be selected raising those jacks so that their master butts 125 will be engaged and raised by a cam 131 which normally is employed to raise jacks and needles for determining wrap areas. This cam 131 is further shown in Figs. 20, 21, 27 and 33. The cam 131 is slidable outwardly to some extent, but is normally spring pressed inwardly by the spring 132. The outward movement is merely for safety in the event of improper contact with passing butts, and this cam might normally be considered as a fixed cam in contrast to other cams which are purposely movable and are automatically so manipulated. For example, cam 133 slightly above and to the right, Fig. 38, is slidable along the side of the cam 131 but is automatically moved to and from butt engaging position at the proper intervals in the cycle of knitting.

Cam 133 has a stem 134 and is maintained in slidable relationship by a shoulder screw 135 engageable, one-half in a slot in the stem of the cam 131 and the other half in the stem 134 of cam 133. A spring (not shown) will normally urge this cam 133 inwardly toward the needle circle, the cam being drawn outwardly by a depending arm 136, Figs. 21, 27 and 34. This arm 136 is fixed to a spindle 137 pivoted in bearings in the upstanding lugs or ears 138 and 139 which are part of a bracket 140, Figs. 21 and 27. The spindle 137 extends angularly as at 141, this extension connecting at 142 to a depending link 143. The arm 136 engages an angular projection 144 which is an integral part of the cam stem 134.

The cam 133 is employed during the knitting of elastic only and serves to raise needles which are to take the elastic to a slightly greater height than that to which they would be raised by cam 131 alone. The cam 131 functions without cam 133 except during the knitting of elastic, that is, during the knitting of wrap yarn patterning.

Referring to Figs. 20, 21 and 27, additional controlling means with that for cams 131 and 133 is shown. This control is for the top plunger 129. That plunger has an extension 145 which is engaged by the end of a depending arm 146 of a bell crank lever pivoted at 147. This bell crank also has a more or less horizontally disposed arm 148 and is in turn connected to the link 143. Upward movements of the link will withdraw both plunger 129 and cam 133; movements in the opposite direction allow the plunger and cam to move inwardly for the engagement of such jack butts as are designed to contact them. The plunger 129 tends to be moved inwardly against the cylinder by a spring (not shown).

Now referring to Figs. 20, 21, 26, 29, 30 and 38, a cam 149 has the stem 150 adapted to slide in a groove in a part of the circular base or an extension thereof. In the same groove is mounted 5 a second cam 151 having a stem 152, the stems 150 and 152 both being grooved at the inner or adjacent sides and being retained in the above mentioned slot by a shoulder screw 153. These cams are likewise movable inwardly to butt engaging position and outwardly to an inactive position, the cam 149 functioning during wrapping along with another cam 154. The cam 154 raises needles which have been selected by plungers 130, that is, completes the second stage of selection 10 as employed for such purposes as knitting color within color patterns. The cam 149 is a latch clearing cam for all needles during the knitting of wrap patterns. This cam is movable inwardly and outwardly at desired times and assures that 15 all needles clear after wrapping has taken place and prior to taking yarn beneath the center cam 105 and knitting beneath stitch cam 106. Obviously the cam 149 will not be in active position during knitting the elastic top. Cam 154 is 20 spring pressed and is what might normally be termed a fixed cam similar to the cam 131.

The cam 151 is controlled to be radially movable to and from butt engaging position and functions along with two other cams 155 and 156, 25 Figs. 20, 21, 26, 31, 32 and 38. Cams 155 and 156 are radially slidable in a bracket 157 at the upper end of a post 158. The cam 155 is radially movable by a lever 159 pivoted at 160 and further connected to the cam stem by a screw 161. 30 Movements of the lever 159 draw the cam outwardly or allow it to move inwardly at appropriate times. The cam 156 has a spring 162 which connects at the outer end of the cam stem and tends to urge that cam inwardly. The cam 155 connects to the cam 156 by means of a depending extension 163 at its outer end engageable in a notch at the outer end of the stem of cam 156. Thus the spring 162 tends to urge both 35 cams inwardly and the lever 159 serves to pull both of them outwardly when that action is desired.

A wire link 164 is connected to lever 159 and also to one arm 165 of a bell crank which pivots at 166 and has a second arm 167 connecting to a depending link 168. Movements of this bell crank will withdraw the two cams 155 and 156 or allow them to be moved inwardly to butt engaging position. Cam 155 merely serves as a leveling cam acting upon butts 127 and 128 for that purpose. Cam 156 is similar to the plungers 129 and 130 and engages the top selecting butts 126 which were engaged by the uppermost plunger 129 thereby selecting jacks 124 beneath those needles which are to be raised at the main cam 40 block for taking yarn and knitting during the production of a tuck top or other tuck area in the elastic portions of a fabric. Such jacks as are selected by the cam 156 will be raised to a height so that master butts 125 will engage cam 151, this latter cam having been moved inwardly at that time, and thereby raise needles to a clearing position. Such needles as are no thus raised will merely pass along at a yarn taking level 45 but do not clear their latches and therefore tuck.

The cam 151 is movable outwardly by means of a second wire link 169 which connects to the same bell crank as the link 164, it being evident that cams 155, 156 and 151 move together. They 50 are employed for knitting the tuck courses and

are not in position at any other part of the knitting.

Cams 170 and 171, Fig. 38, are merely employed as jack raise cams while the cam 172 is for the purpose of pushing jacks downwardly to a lowermost level prior to a time when they would be pushed down by needles knitting under stitch cam 106.

The cam 173, Figs. 36, 37 and 38, is a fixed cam and serves the purpose of pushing jacks downwardly after they have completed the selection and raising of needle at the first station, that is, by plungers 129 and cams 131 and 133. This cam functions both during the knitting of elastic work and during wrap patterning.

Referring to Figs. 28, 35 and 38, cams 174 and 175 are plain sole cams and work only during patterning as in the high-splice or sole and instep areas to inhibit the knitting of a pattern in the high splice and sole. These cams function on long butts 128 and push down certain selected jacks before they may contact either of cams 131 or 154. These cams 174 and 175 have stems 176 and 177 which have projections 178 and 179 engageable by levers 180 and 181 and which are automatically moved so as to hold these plain sole cams outwardly except at the particular phases in the knitting cycle at which they are to function. Their action is well-known and need not be described in detail in this case.

Now referring to Figs. 16, 19, 38 and 39, cam 108 is slideable inwardly and outwardly on the cam 107, having a stem at 182 with a pin 183 projecting upwardly at the outer end of that stem and to which is connected a spring 184 under tension and connected to a hook 185 fixed to top center cam 105. A second stem or screw 186 projects downwardly and is engaged by the end of a lever 187 pivoted at 188 and having connection to a link 189 by means of which the lever may be moved for withdrawing the said cam 108 at desired times. This cam 108 is withdrawn when the tuck courses are to be knitted. At all other times it is or at least, may be held in innermost position. Of course, the front stitch cam 104 is withdrawn during the knitting of the tuck courses, and incidentally, in this type of machine, is withdrawn at all times except in the knitting of a heel or toe.

Now referring to Figs. 22-25, the sinker cap 190 has sinker cams 192, 193 and a center sinker cam 194 at the main side of the machine, these being the usual cams employed. The second sinker cam 195 is pivoted at 196 and has an extending arm 197 connected by means of a spring 198 to a fixed part of the sinker cap mechanism so that, in effect, this is a sort of flopper cam which may be moved inwardly by means of a contact element 199 engageable with a pin 200 in an extension 201 of the cam itself. These parts are also common to the Banner 19-step wrap machine and their function is well understood. At the elastic yarn feed the sinker cap is supplemented by a plate 202 beneath which slides a stem 203 carrying at its inner end an auxiliary center sinker cam 204. At either side of this cam are fixed sinker cams 205 and 206. The ends of the center sinker cam 204 are guided by extensions or plates 207 and 208, these being fixed to maintain sinkers downwardly in their slots since a considerable part of the cap itself is cut away at this particular point. A spring 209 urges the stem 203 inwardly, it being pulled outwardly at the desired times by contact of the lever 121, Fig. 17, with a lug 210 at the end

of the cam stem, the action at this point being practically identical with that previously described with respect to similar parts performing a similar function in the first described form of the invention. Of course, the cam 204 is moved outwardly to active position during the knitting of the elastic yarn, but is allowed to move inwardly at other times.

Operation

Now referring to Figs. 38 and 39, a brief discussion of the operation will be given, this being specific to the form described as a modification. In Fig. 38 the pathways of needle and jack butts have been shown as when knitting an elastic top and tucking at certain wales during that process. The jack butts 125 are leveled by the raise cam 170 and the plunger 129 put in position to engage such of the butts 126 as pass it; jacks affected thereby will be raised from a pathway 211 to a pathway 212 whereupon the cams 131 and 133 will elevate those selected jacks to a considerably greater height, needles being raised correspondingly to the pathway 213. This pathway 213 assures that the elastic yarn *e* will be taken in the hooks of needles. Cam 131 is sufficient to raise needles to a height for clearing latches, but since the elastic yarn is preferably fed at a relatively high level, cam 133 imparts the additional movement necessary to take the elastic yarn at that relatively elevated position. The cam 133, as has been described, is movable and is employed for the purpose above explained. During ordinary knitting at which a wrap pattern is being made cam 133 will be withdrawn.

Needles that have taken the elastic yarn are drawn down by the cam 111 and knit drawing independent elastic yarn stitches. The other needles which were merely moving along at a raise cam level as determined by the cam 214 move down this cam 111, but have not taken yarn nor cleared their latches so that this is more or less an idle movement. Of course, the same control which moved stitch cam 111 into an effective position has drawn the auxiliary sinker cam 204 out so that a sinker wave is set up along with cooperating stitch wave. After these elastic stitches are drawn cam 215 immediately raises all needles to a raise cam level at which they move along beneath cam 105 until they contact the stitch cam 106, except for the fact that in tucking, certain needles are raised to a latch clearing and yarn taking level 216, this being done by jack control as will be presently described. The plungers 130 will not be in position for affecting jacks during the knitting of the elastic top and cam 154, although the same is in active position, will have no effect since no jacks are raised by said plungers. The cams 155, 156 and 151 will be moved inwardly to active position, cam 108 being withdrawn. The cam 171 raises jacks and levels them prior to selection by the cam 156. That selection is similar to the selection determined by the plunger 129. The cam 149 which is employed during wrap stripe knitting only and which is a standard part of Banner 19-step wrap machines is withdrawn by mechanism not shown herein. Those jacks selected by the cam 156 are raised by the master cam 151 thereby elevating needles so that their butts travel in the pathway 216. Those needles thus raised will take a main knitting yarn *y* and will knit. The remaining needles also take the yarn, but since they did not clear their latches, will merely tuck. This tucking will continue so long

as desired until cams 155, 156 and 151 are withdrawn at which time cam 108 is projected inwardly to perform its latch clearing function. The front stitch cam 104 is in inactive position during the knitting of the entire elastic top.

In knitting elastic fabric as in United States Patent #2,131,720 the tuck courses may be knitted at any desired intervals and may comprise as many courses in any individual tuck area as desired or may conveniently be knitted. When tucking is not being done, knitting merely continues as above described except that the cam 108 remains in position so that all needles clear and knit at the so-called main side of the machine.

Now referring to Fig. 39, knitting is shown in a reverse or clockwise stroke in reciprocatory work as in a heel or toe. At such time jacks are merely controlled by the cams 172, 171 and 170 in the direction illustrated, and in counter-clockwise strokes, pass over cams 170 and 171 and are moved down by cam 172 in that order. Needles are merely controlled in the usual way to knit first in one direction and then in the other beneath cams 104 and 106. The movable cam 108 is in position at this time, also it is to be understood that the cam is not necessarily in active position, since both stitch cams are in and control needles for clearing the knitting in the usual way. At this time all movable cams effective upon jacks are withdrawn as are the stitch cam 111 and sinker cam 204.

The invention has been described in more or less specific terms and by reference to specific machines merely by way of illustrations. The disclosure is broadly inclusive of variations which will be apparent as applicable to machines of similar type. It is not to be limited other than by the scope of the appended claims.

We claim:

1. In a knitting machine the combination of means for feeding an elastic yarn, means for feeding a non-elastic yarn at a separate feeding point, means for separating needles whereby spaced needles only will take the elastic yarn and means for drawing that yarn into independent knitted stitches, means for raising needles to a yarn taking but not to a latch clearing position prior to taking the non-elastic yarn and supplemental means movable to and from active position under definite pattern control for raising spaced needles only to clear latches at this non-elastic yarn feed whereby certain of the needles will knit and others will tuck.

2. In a knitting machine the combination of two independent yarn feeds, one said feed being employed for elastic yarn and the other for feeding a non-elastic yarn, cams for causing needles to knit at each feed, and at the said elastic yarn feed, means for raising spaced needles to take 60 and to knit the elastic yarn including jack selecting means for determining a wrap yarn pattern and other means for raising selected, spaced jacks and needles to a yarn taking level.

3. In a knitting machine the combination of separate and independent elastic yarn feeding means and non-elastic yarn feeding means, cam means for causing the drawing of elastic yarn stitches at the first feed and non-elastic yarn stitches at the second mentioned feed, means 70 for selecting spaced needles to take the elastic

at the first feed, and at the second feed, cam means for controlling all needles so that they rise to an elevation at which the non-elastic yarn will be taken in their hooks but at which needles would not clear latches and supplemental, pattern controlled means operable throughout predetermined courses to raise some needles only to a latch clearing level.

4. In a knitting machine the combination of 10 yarn feeding means for an elastic yarn, separate and independent feeding means for a non-elastic yarn, needles and jacks and wrap yarn feeding means for introducing wrap yarns to selected needles, a series of cam means operable on jacks for selecting needles to determine the wrap pattern, the construction being such that one at least of said cam means is independently controlled for affecting jacks so as to raise spaced needles to take elastic yarn at desired times, 20 means for raising selected jacks and their needles so that the needles clear latches and take the elastic yarn, cam means for raising all needles to a yarn taking level at the non-elastic yarn feed and supplemental cam means pattern controlled and operable upon jacks for elevating those same jacks and needles which were selected to take the elastic yarn to clear latches at the said non-elastic yarn feed.

5. In a knitting machine the combination of 30 an elastic yarn feed, a non-elastic yarn feed, means for selecting needles and raising them to latch clearing position at the elastic yarn feed and causing needles to knit thereat, cam means at the non-elastic yarn feed including a movable center raise cam for clearing all needle latches, 35 and in conjunction therewith, means for raising some only of the needles to a latch clearing level.

6. In a knitting machine the combination of 40 an elastic yarn feed; a non-elastic yarn feed, separate cam means at each feed for independently causing needles to draw stitches, selecting means at the elastic yarn feed for raising spaced needles to clear their latches and to take the elastic yarn, selecting means at the non-elastic yarn feed for raising the same spaced needles to clear their latches whereby all needles take elastic yarn, but spaced needles only clear latches and knit at the non-elastic yarn feed, and a movable center raise cam for causing all needles to be raised to latch clearing position at this non-elastic yarn feed.

7. In a knitting machine the combination of 55 two yarn feeding stations at one of which elastic yarn is fed and at the second non-elastic yarn is fed, needles and independent jacks beneath needles whereby they may be selected for determining the knitting of certain patterned areas, selecting means for said jacks adapted to raise needles to a predetermined level for receiving pattern threads and a movable cam functioning in conjunction therewith whereby during the knitting of elastic yarn, the pattern means is employed for determining spaced needles which are to take the elastic and whereby said movable cam elevates needles to a higher position than that to which they would be raised by the pattern determining means only.
